AUTOMATIC TYPEWRITER CONTROL CONSOLE

John S. Kovacs, East Norriton, and Lewis H. Herr, Lansdale, Pa., and Richard H. Penney, New York, N.Y., assignors to Sperry Rand Corporation, New York, N.Y.

Filed Mar. 27, 1972, Ser. No. 238,756

Term of patent 14 years

Int. Cl. D14—02

U.S. Cl. D26—5 C

FIG. 1

FIG. 4

FIG. 5

FIG. 3

FIG. 2

FIG.6

FIG. 9

FIG. 10

FIG. 8

FIG. 7

FIG. 1 is a front perspective view of an automatic typewriter control console showing our new design;

FIG. 2 is a rear elevational view thereof;

FIG. 3 is a left side elevational view thereof, the right side being similar thereto;

FIG. 4 is a front elevational view thereof;

FIG. 5 is a top view thereof;

FIG. 6 is a front perspective view of a modified form of the automatic typewriter control console shown in FIG. 1;

FIG. 7 is a rear elevational view of FIG. 6;

FIG. 8 is a left side elevational view of FIG. 6, the right side being similar thereto;

FIG. 9 is a front elevational view of FIG. 6; and

FIG. 10 is a top view of FIG. 6.

We claim:

The ornamental design for an automatic typewriter control console, substantially as shown and described.
